Fig. 3.

UNITED STATES PATENT OFFICE.

HENRY A. FLECK AND CHARLES H. FLECK, JR., OF PHILADELPHIA, PENNSYLVANIA.

STREET AND STATION INDICATOR.

1,159,484.

Specification of Letters Patent.

Patented Nov. 9, 1915.

Application filed October 16, 1914. Serial No. 866,930.

To all whom it may concern:

Be it known that we, HENRY A. FLECK and CHARLES H. FLECK, Jr., both citizens of the United States, residing in the city and county of Philadelphia, State of Pennsylvania, have invented a new and useful Street and Station Indicator, of which the following is a specification.

Our invention consists of a street and station indicator adapted to be mounted on a car, the same being composed of an apron or sheet on which the names of streets and stations appear in succession, rollers, reels or drums on one of which said apron may be wound and from the other of which said apron may be unwound, a spring serving as a power to cause the proper motion of said apron, a dog or pawl, and a ratchet device for controlling said motion intermittently, and means for operating said dog embodying a solenoid and an electric connection for the same and the feed wire along the car tracks or railroad, whereby the indicator may be operated automatically on approaching or arriving at the next street or station.

It consists of novel means for re-winding the apron after it has been unwound, to sufficient extent from its roller, reel or drum.

The invention is satisfactorily illustrated in the accompanying drawing, but the important instrumentalities thereof may be varied, and so it is to be understood that the invention is not limited to the specific details shown and described.

Figure 1 represents a front elevation of a street or station indicator embodying our invention. Fig. 2 represents a rear view thereof. Fig. 3 represents a side elevation thereof on an enlarged scale taken from the right hand of Fig. 1. Fig. 4 represents a vertical section on an enlarged scale on line $x-x$ Fig. 1. Fig. 5 represents a vertical section on an enlarged scale taken on line $y-y$ Fig. 1. Fig. 6 represents a partial section and partial side elevation of a portion of the apron-rewinding mechanism. Fig. 7 represents a perspective view of the feed wire of a trolley line and the means employed therefrom for energizing the solenoid hereinafter referred-to. Fig. 8 represents a vertical section of the solenoid.

Similar numerals of reference indicate corresponding parts in the figures.

Referring to the drawings, 1 designates an apron on which the names of streets and stations are printed, painted or otherwise placed (one being shown at 2), the same being adapted to be unwound from and wound upon the rollers, reels or drums 3 and 4 which are mounted one below the other on the side plates 5 of the frame of the device. Connected with one of said plates is the spring 6 whose barrel or casing 7 has the gear wheel 8 connected therewith. Connected with one of the axles or journals 65 of the roller 4 is the pinion 9 which by means of intermediate pinions 10 on said side plate is geared over to the wheel 8 whereby the unwinding of the spring 6 imparts rotary motion to the roller 4, so as to cause the apron 1 to be wound on said roller, while the latter is drawn down so as to be unwound from the roller 3, so that the name of a street or station will be presented to the front at the place on the apron intermediate of the rollers 3 and 4, it being noticed that the mechanism of the device is inclosed in a suitable casing shown in dotted lines in Fig. 1 and having an opening in front through which the name of the street or station on the apron is visible, these features *per se* being known in the art.

In order to control the unwinding of the spring so that unwinding and winding of the apron will be at intervals to cause the names of the streets or stations to be presented successively to view there is connected with one of the journals or axles of the roller 3, the ratchet 11 with whose teeth engages the nose of the dog or pawl 12 which is connected with the adjacent side plate 5 by the pivot 13, said dog having in its lower end the crank pin 14 which enters freely the slot 15 of the cam member 16, said slot being comparatively V-shape, the latter being connected with a solenoid which is composed of the core 17, and a suitable coil of wire 18 forming a magnet, said coil having connected with it the conductor 19 which extends from the car to the electric feed wire therefor and is adapted to engage with intermediate circuit-forming and clos-

ing devices as hereinafter described located adjacent to the approaching street or station so that the solenoid will be operated in advance of said street or station, whereby the magnet will be energized and the core 17 raised, and with it the cam member 16, the lower diagonal limb of the slot 15 of the latter riding over the crank pin 14 so as to raise the latter, and with it the connected end of the dog 12, whereby the nose of the dog will be withdrawn from the tooth of the ratchet with which it had been engaged to control said ratchet thus releasing the ratchet so that the spring 6 unwinds and becomes operative to exert its power on the lower roller 4, and rotate it whereby the apron 1 is wound on said drum, and it draws itself from the upper roller 3 so as to be unwound from the latter, the distance required to present the name of the next or coming street or station on the front visible part of said apron the teeth of the ratchet 11 being timed or spaced to accomplish the proper movement of the apron, the extent of rotation of the rollers being equal to the distance between adjacent teeth of the ratchet. Then the circuit of the conductors is broken, whereby the solenoid drops and the cam 16 operates the dog, so that its nose rises and is placed in the path of the advancing tooth of the ratchet engaging with the shoulder thereof, thus locking the ratchet and preventing movement of the apron and rollers and holding the spring in check until the magnet is again energized, when the core is raised again and the other operations stated are repeated.

When the apron has been unwound fully or sufficiently from the roller 3, it requires to be re-wound upon the same, and for this purpose there is connected with the axis of said roller the pulley 20, around which is passed the endless belt 21 which passes also around the wheel 22, the latter being mounted on the lever 23 which is pivotally connected with the lower portion of the adjacent side plate 5 of the frame of the device, said wheel 21 being provided with the crank handle 24 whereby it may be rotated. When said lever is in horizontal position or approximately so, the belt 21 is loose on the wheel 22 so does not impart motion to the latter, whereby said wheel and the crank handle thereof remain at rest during the shifting of the apron, but when said lever is lowered, the wheel 22 follows the same, and so contacts with the lower portion of the belt 21 so as to tighten the belt thereon. Now the wheel may be rotated by the crank handle whereby the belt rotates the wheel 20 and with it the roller 3, thus drawing up the apron and rewinding the latter upon said roller.

As the ratchet 11 now rotates in the di-

rection opposite to that shown by the arrow 65 Fig. 5, its teeth ride freely over the nose of the dog 12, the crank pin oscillating freely in the upper diagonal limb of the slot 15 until the winding of the spring is ceased when the nose of the dog drops into engagement with the adjacent tooth of the ratchet and so controls the latter, whereby the apron is held at rest until the solenoid is again raised, the effect of which is evident.

Referring to Fig. 7, the circuit forming 75 and closing devices hereinbefore referred to consist of the contact piece 24 which is connected with the trolley pole 25 and is insulated therefrom. On the support 26 of the feed wire 27 in the contact piece 28 which 80 is suspended from the insulating member 29 on said support.

The contact piece 28 is in electrical communication with the feed wire 27 by the connecting wire 30, consequently when the 85 piece 24 reaches the piece 28 and contacts therewith the electric circuit is formed between the feed wire 27 and the conductor 19, and thus the magnet is energized and the solenoid operated with the result as hereinbefore stated.

Attention is directed to the fact that the dog or pawl 12 has a plurality of noses 81, so that when one of the same is withdrawn from the shoulder of the tooth with which it 95 is engaged, and it lowers therefrom whereby the ratchet 11 is permitted to rotate, the other nose is raised and contacts with the curved outer surface of said tooth and bears against the same somewhat tangentially, 100 whereby it assists the ratchet to revolve, a feature of importance should said ratchet stick on its bearings or be otherwise stopped by its gearing working improperly, or the spring 6 should fail to unwind or lose its 105 full power to perform its operation.

Having thus described our invention what we claim as new and desire to secure by Letters Patent, is:—

1. In a street and station indicator for a 110 car, an apron, rollers on which and from which said apron may be wound and unwound, a spring power adapted to operate one of said rollers, a ratchet on said roller, an oscillatory dog adapted to engage the 115 teeth of said ratchet, a solenoid, a slotted cam rigid with and upwardly continuous of the core of said solenoid and movable in alinement therewith, a slidable connection between said cam and dog, and means for 120 energizing the magnet of said solenoid.

2. In an indicator, a revoluble member, a ratchet thereon, a pivotally mounted pawl having noses of different lengths adapted for co-operation with said ratchet, and electric means controlling and actuating said pawl, said means embodying a solenoid, a cam connected with the core thereof and

having an angular shaped slot and a crank pin movable with said pawl and adapted to oscillate in both limbs of said slot.

3. In a street and station indicator for a car, an apron, a roller on which and from which said apron may be rewound, and a rewinding device for said apron on said roller consisting of a wheel on said roller, a swinging lever mounted on the frame of the de-

vice, a wheel having its bearings on said lever, and an endless belt adapted to pass around said wheels.
